(57) **CLAIM**

The ornamental design for a beverage fountain, as shown and described.

DESCRIPTION

FIG. 1 is a top perspective view of the beverage fountain showing the new design;

FIG. 2 is a bottom perspective view thereof;

FIG. 3 is a front elevation view thereof;

FIG. 4 is a side elevation view thereof;

FIG. 5 is a top plan view thereof; and,

FIG. 6 is a rear elevation view thereof.

The broken lines are for the purpose of illustrating environment and form no part of the claimed design.
